UNITED STATES PATENT OFFICE.

JOSEPH GUMBER, PAUL GUMBER, AND JOHN HARDER, OF EAST MOLINE, ILLINOIS.

ROLLING SCREEN.

1,215,651.

Specification of Letters Patent. Patented Feb. 13, 1917.

Application filed March 27, 1916. Serial No. 87,015.

To all whom it may concern:

Be it known that we, JOSEPH GUMBER, PAUL GUMBER, and JOHN HARDER, citizens of the United States, residing at East Moline, in the county of Rock Island and State of Illinois, have invented certain new and useful Improvements in Rolling Screens, of which the following is a specification, reference being had to the accompanying drawings.

This invention relates to rolling screens for windows, porches and the like and has for one of its objects to generally improve the construction of screens of this character whereby they may be applied to various styles of building structures for efficient operation.

Another object of the invention is to provide means to prevent lateral movement of the screen but which will permit of free vertical or rolling movement of the same.

A further object of the invention is to provide means whereby one screen may be substituted for another in a minimum of time and with but slight labor, it being unnecessary to in any way dismount the rolling mechanism to accomplish such substitution.

Still another object of the invention is to provide a spring actuated roller for supporting the screen and to provide means to positively hold the screen in a lowered position against the action of the spring.

With the foregoing and other objects in view, the invention consists in the novel features of construction, combination and arrangement of parts as will be hereinafter more fully described, illustrated in the accompanying drawings and claimed.

In the drawings,

Fig. 1 is a vertical sectional view illustrating the application of the improved screen to a window;

Fig. 2 is a front elevation with parts in section;

Fig. 3 is a detail view illustrating the manner of mounting the roller casing;

Fig. 4 is a detail view showing the manner of preventing lateral movement of the screen;

Fig. 5 is a detail view of the connection between the straps and the screen;

Fig. 6 is a detail section through one of the clips carried adjacent the edges of the screen;

Fig. 7 is a detail vertical section showing the manner of securing one of the straps to the upper edge of the screen;

Fig. 8 is a detail vertical section showing the manner of removably attaching the straps to the screen;

Fig. 9 is a vertical section of a slightly modified form of screen;

Fig. 10 is a similar view of another slight modification; and

Fig. 11 is a detail vertical section showing the manner of retaining the screen in a lowered position.

Referring to the drawings by numerals, 1 designates the frame of a window which is carried by a sub-sill 2 in turn mounted upon the sill 3, while 4 indicates the outer frame structure of the building to which the frame is applied. Stops 5 and 6 are arranged within the frame and these stops have slidably abutting thereagainst the upper and lower sashes 7 and 8 respectively, openings 9 being provided in the lower edge of the frame 4 adjacent either side of the window frame 1 and similar openings being provided in the sides of the frame 1 adjacent the openings 9 for a purpose which will presently appear.

A casing for the screen supporting roller is provided which includes a straight rear wall 10, straight upper and lower walls 11 and 12 and a curved outer wall 13 which connects the upper and lower walls, a flange 14 being extended rearwardly from the lower edge of the rear wall to form a support for the means employed for attaching the casing in an operative position upon the window frame. This roller casing is formed from any desired material, such as sheet metal and is closed at its ends, as indicated at 15.

Brackets 16, of substantial U-shape are secured to the flange 14 adjacent the ends of the casing and have the spaced arms 17 thereof projecting outwardly from the casing and provided with aligned openings to receive a pin 18, which has one end projecting beyond the outer of the arms so as to be received in one of the openings in the frame 1 to retain the casing thereon. As will be understood, one of these brackets is provided adjacent either end of the casing for supporting a pin or engagement with the opening in either side of the window frame and in order to provide means whereby these pins may be disengaged from the

openings, to permit of the removal of the casing, a coiled expansion spring 19 is provided which is arranged in abutting relation with one of the arms of each of the 5 brackets and exerts a tension against a pin 20 carried by each of the pins to force the pins outwardly and into engagement with the opening, a knob or handle 21 being provided upon the inner end of each of the pins 10 to form a hand grip whereby the pin may be retracted against the action of the coil springs to disengage the same from the openings. By retracting the pins 18 and engaging the pins 22 carried by the upper 15 wall 11 of the casing, with the openings 9 and then releasing the pins 18, the casing may be attached to the window frame quickly and efficiently and may be as quickly removed therefrom in a like manner, should occasion demand.

The end walls 15 of the casing are depressed inwardly and circumferentially as at 23, so as to provide a supporting flange for a pole 24 which is of circular shape in 25 cross section and extends throughout the length of the casing, being rigidly mounted therein by means of screws or other fastening elements 25 which are passed through openings in the end walls and threaded into 30 the ends of the pole.

Spacing rings 26 are provided which are of a size to be snugly and rotatably received upon the pole 24, the said rings being arranged one adjacent either end of the pole 35 and being of substantial U-shape in cross section so as to support in spaced relation to the pole a tubular cylindrical casing 27 forming a roller for supporting the screen. The roller 27 is of substantially the same 40 length as the casing and is preferably rigidly mounted upon the spacing rings 26. A coil spring 28 is arranged about the pole 24 between the pole and the roller 27 and has one end secured to one of the rings 26 and 45 its other end secured to the pole so that rotation of the roller will tension the same to cause the roller to be returned to a normal position upon its release.

Spaced slots 29 of any desired length are 50 formed in pairs and in alinement throughout the longitudinal extent of the roller so as to provide arms 30 to permit of attaching to the roller, the inner ends of straps 31, any desired number of these straps being 55 provided which are of a length to extend through a slot 32 adjacent the lower edge of the rear wall 10 of the casing and extending throughout its length, the said slot being formed by deflecting inwardly a portion 33 of the lower wall 12 of the casing 60 to provide a guide flange to prevent fraying of the straps or screen as the same are operated. The outer ends of the straps extend exteriorly of the casing through the slot 32 65 and are doubled upon themselves after be-

ing passed through links 34, as indicated at 35 so that bands 36 may be engaged therewith to secure the links to the straps.

The screen indicated at 37 is provided at its upper edge with a longitudinally extending metallic strip 38 which is suitably bent to clamp the upper edge of the screen and which carries the links 34. In practice, the screens are provided with the strips 38 and links 34 permanently secured thereto so that by removing the straps from engagement with the links, one screen may be removed and another substituted.

The screen is of sufficient length to entirely overlie the window and carries at its 80 lower edge a stiffening strip 39. This strip 39 is formed preferably of sheet metal which is bent intermediate its longitudinal edges to receive between the arms, thus provided, the lower edge of the screen, the said strip, as an entirety being bent at right angles to itself in cross section so as to provide a relatively broad bearing portion for engagement with the sill.

By exerting a pull upon the strip 39, after the screen has been wound upon the roller 27, the screen may be moved to overlie the window, the roller 27 rotating against the action of the spring 28, as the screen is moved downwardly, as will be understood, 95 while upon release of the screen, the spring so tensioned will rewind the same upon the roller. If desired, a suitable ratchet mechanism such as that commonly employed in connection with the rollers of window curtains may be provided to permit of the screen being retained in any desired vertically adjusted position relatively to the window.

In order to provide means to positively 105 retain the screen in a lowered position, the sub-sill has threaded therein a pin 40 which is provided with a shank 41 and head 42, said head being flattened upon opposite sides so as to permit the same to be passed through 110 an elongated opening 43 in the strip 39 after the screen is lowered so that the pin may then be rotated slightly to cause the inner faces of the flattened head to engage with the outer face of the strip to lock the same 115 against outward movement relative to the pin, and thus retain the screen in a lowered position.

In frames where no sub-sill is provided, a strip 44 may be secured to the sill 3 and 120 this strip may have journaled therein one or more pins 41 for the purpose previously mentioned.

In order to provide means to permit of free vertical movement of the screen, but to prevent outward or side-wise movement of the same, the window frame may have secured thereto strips 45 which extend vertically of the frame in spaced relation to the outer stops 5. These strips 45, one being 130

provided for each side of the frame, each comprise a base portion 46 from which extends at right angles, a portion 47 which in turn has the outer longitudinal edge thereof bent at right angles to itself as at 48, thus coöperating with the stop 5 to form a housing to receive the opposite side edges of the screen. A plurality of clips 49 are secured to the outer face of the screen adjacent its opposite side edges so as to be received by the housings, provided by the strips 45. Each of these clips comprises a hollow cylindrical member 50 which is provided upon its inner face with an opening to permit the intermediate portion 51 of a pair of pliable arms 52 to be arranged therein. The arms are adapted to be inserted through the mesh of the screen and engage with the screen in any suitable manner so as to firmly retain the caps thereon. By this arrangement, it will be noted that the screen is permitted of free vertical movement but, because of the engagement of the clips with the strips 45, lateral movement of the screen in any direction is prevented.

By slight alterations to the structure as just described, it will be obvious that the same may be applied to the interior, as well as the outer portion of a window frame or may be applied to a porch or the like, where screens are commonly used.

Since brick structures are somewhat different from frame structures, we have illustrated a slight modification of the invention whereby the same may be readily applied to structures of this character. Instead of providing adjustable pins for engagement with openings in the supporting structure, one wall of the casing is extended, as at 53, so as to overlie a portion of the frame, screws 54 or other fastening elements being passed through the flange and engaged with the frame to rigidly support the casing in a desired position. Likewise the end walls of the casing may be extended, or strips secured to the same, as indicated at 55, through which other fastening elements 56 may be passed and engaged with the jamb, the structure of the device otherwise remaining the same as that illustrated in connection with the preferred embodiment of the invention.

Frame buildings being somewhat different from other structures, an embodiment of the invention has been illustrated whereby the same may be readily applied to this class of buildings. The flange 53 is extended at a slightly different angle from the casing than the flange 53 and the support 60 55' instead of being bent for engagement with the jamb, is merely extended straight and provided with an opening or openings through which fastening elements may be passed to secure the casing to the frame.

65 From the foregoing description taken in

connection with the accompanying drawings, it is thought that the construction, operation and advantages of the improved rolling window screens will be clearly understood and while we have herein shown and described certain specific embodiments of our invention, we do not wish to be limited thereto except for such limitations as the claims may import.

We claim:

1. A device of the character described comprising in combination with a supporting structure, a casing mounted thereon, said casing being closed at its ends, a portion of the ends being pressed inwardly to provide supporting flanges, a pole supported by said flanges, a roller mounted upon said pole, and a screen carried by said roller.

2. The combination with a supporting structure, of a casing, spring latch devices carried by the casing to coöperate with the supporting structure and detachably sustain the casing in position thereon, a spring-actuated roller mounted in the casing, and a screen connected to said roller.

3. A device of the character described comprising in combination with a supporting structure, a casing mounted thereon, a roller mounted within the casing, straps carried by said roller, a screen, and a detachable connection between the straps and the screen.

4. A device of the character described comprising in combination with a supporting structure, a casing mounted thereon, a spring actuated roller mounted within the casing, straps secured to said roller, a screen, links carried by said screen, and a detachable connection between the links and the straps.

5. A device of the character described comprising in combination with a supporting structure, a casing mounted thereon, a roller mounted within said casing, a screen, a strip secured to said screen, straps secured to the roller, links carried by the strip, said straps being adapted for engagement with the links, and slides for engagement with the straps to secure the same to the links.

6. The combination with a supporting structure having spaced openings, of a casing, a roller arranged within the casing, a screen connected to the roller to be wound thereon, and spring-actuated pins mounted upon the casing for engagement in the openings in the supporting structure to detachably retain the casing in position thereon.

7. A device of the character described comprising in combination with a supporting structure, a casing, a roller arranged within the casing, a screen carried by the roller and extending exteriorly of the casing, said supporting structures having openings formed therein, pins carried by the casing for engagement with certain of

4
said openings, and other spring actuated pins for engagement with other of the openings to detachably mount the casing upon the supporting structure.

- 5 8. A device of the character described comprising in combination with a supporting structure, a casing, a roller mounted within said casing, a screen carried by said roller, brackets carried by the casing, pins 10 slidably arranged in said brackets, springs engaging said brackets and said pins to hold the same in engagement with the supporting structure, and other pins carried by the cas-

ing and coöperating with said first pins to detachably mount the casing upon the 15 supporting structure.

In testimony whereof we hereunto affix our signatures in the presence of two witnesses.

JOE GUMBLE.
PAUL GUMBER.
JOHN HARDER.
